UNITED STATES PATENT OFFICE

AUSTIN H. DOWNS, OF NEWARK, NEW JERSEY, ASSIGNOR TO ECLIPSE AIR BRUSH COMPANY, INC., OF NEWARK, NEW JERSEY, A CORPORATION OF NEW JERSEY

DEVICE FOR SPRAYING PAINTS, LACQUERS OR OTHER LIQUIDS

Application filed January 14, 1927. Serial No. 161,066.

This invention relates to improvements in devices for spraying paints, lacquers or other liquids, as well as heavy liquids, semi-pastes, etc., and while it is designed principally for 5 coating for decoration and protection, has uses in other arts as well.

The principal object of the invention is the provision of such a device which is simple and compact in construction and which may 10 be readily assembled and disassembled and which is highly efficient in operation and simply and readily controlled to use a minimum amount of material and a minimum amount of pressure to accomplish the best results.

Another object includes the provision of 15 such a device in which the trigger operates directly upon the air supply valve and a liquid material supply valve and in which adjusting means is provided on the device for regulating the quantity of flow of air and the pressure of air supplied to the nozzle for atomizing purposes. This permits the device to operate at low pressure and volume and with 20 a low consumption of material, while affording perfect atomization of the material and the application thereof to the surfaces without any disadvantages arising from the operation.

Another object is the provision of such a 25 device in which the entire body including the handle may be made of one piece preferably by die-casting or forging and in which the operating parts may be readily and easily assembled, whereby the manufacture is simplified and cheapened and a very attractive appearing and substantial device is provided. Furthermore, all the operating parts are 30 readily accessible.

Further objects include improvements in 35 details of construction which are hereinafter set forth in full.

To the accomplishment of the foregoing and such other objects as may hereinafter appear, this invention consists in the construction, combination and arrangement of

parts hereinafter described and then sought to be defined in the appended claims, reference being had to the accompanying drawings forming a part hereof and which show, merely for the purpose of illustrative disclosure, a preferred embodiment of my invention, it being expressly understood, however, that various changes may be made in practice within the scope of the claims without 50 disengaging from my inventive idea.

In the drawings—

Figure 1 is a vertical longitudinal section taken through a device constructed to embody my invention.

Figure 2 is a side elevation of the same 60 with the liquid cup attached.

Figure 3 is an exploded view of the various parts comprising the device shown in Figure 1, most of these parts being shown in section.

Figure 4 is a vertical transverse cross section through part of the body to show the air control valve.

Referring now to the drawings the numeral 70 1 designates the body of the device as a whole, this body including the barrel portion 2 and the handle portion 3, the handle portion extending downwardly from the barrel portion and inclined slightly to the rear so that the device has somewhat the appearance of an 75 automatic revolver, the handle portion providing a suitable and comfortable grip for the operator.

Devices of this kind are employed to spray 80 material principally for coating purposes, the material usually being fluid and atomized by air under pressure. This material is fed to the point of atomization by pressure and consequently the device is provided with ports, passages and valves together with operating media for controlling the admission and passage of the pressure fluid as well as the liquid material, and the atomization of the same. A connection 4 to a suitable source of 85 air or other fluid pressure is made with the 90

threaded nipple 5 on the lower end of the handle portion 3. Usually this fluid pressure is automatically maintained at a set or predetermined figure by suitable regulating means, as is well understood and practiced in the art. This nipple 5 leads to the port or passage 6 which extends upwardly through the interior of the handle 3 to the air inlet valve chamber 7. This valve chamber is formed by boring or drilling a passage horizontally through the lower rear portion of the barrel part from the rear end and to and into the space 8 in an intermediate portion thereof. This space 8 is adapted to receive a trigger 9 and permit its operative movement therein. In the forward end of this opening or valve chamber 7 is mounted a bushing 10, which bushing is provided with a longitudinal bore or passage 11 which is enlarged at one end as at 12 to provide an air compartment and which is also formed at this end with the bevelled valve seat 13. A valve 14 is adapted to be seated against said seat 13 and is provided with the plunger or rod 15 slidably mounted in said bore or passage 11 and extending out into the space 8 to be engaged by the trigger 9, as will more fully hereinafter appear. The valve 14 is normally maintained on its seat by means of the pressure of spring 16 which is positioned about the stud 17 on the end of the valve bearing against the valve shoulder 18 at one end and resting within a socket 19 formed from the inner end of the holding and securing member 20. This member 20 is exteriorly screw-threaded for a portion of its length as at 21 to engage the internal screw-threads 22 formed in the air compartment 7 and has the abutment 23 formed to engage the rear end of the barrel portion when screwed home. This member 20 permits the ready assembly and disassembly of the air valve structure. It is to be noted that the port 6 opens into the air chamber 7 at the rear side of the valve and that the bushing 10 is provided with a lateral opening 24 leading to the air port or passage 25 formed in the barrel portion 2 and leading forward. It is also to be noted that the valve plunger or rod 15 has an extended bearing in the bushing 10. The spring 16 normally holds the valve 14 on its seat but when the trigger 9 is moved rearwardly it engages the end of the plunger 15 and moves the valve 14 off its seat, permitting the passage of air from the air inlet into the forward leading air port or passage 25.

The barrel portion 2 extends forwardly and in a horizontal direction from the handle portion 3 and is provided with an apertured lug or flange 26 to provide a convenient hanging arrangement. The trigger 9 is pivoted within the barrel portion as at 27 for a longitudinal swinging movement and the space 8 is in the form of a slot extending from a point near the upper edge of the barrel portion,

down through the barrel portion until it opens through the lower edge of the barrel portion.

The barrel is bored centrally and longitudinally to provide the packing gland and spring chamber 28, which extends for a considerable distance from the rear end thereof, and also to provide a forward compartment 29 which extends into the barrel from the front end to its junction with the chamber 28. A packing gland or sleeve 30 is mounted within said chamber or compartment 28 and has one end concaved or bevelled as at 31, which, when assembled in position, is spaced from the shoulder 32, which is formed at the junction between the two chambers or compartments 28 and 29, as the former is of greater diameter. This space is filled with a suitable packing material which surrounds the liquid valve rod or stem 33, which passes through an opening 34 in the end 31 of the packing gland or sleeve 30, thus affording a bearing for said valve rod. Near its rear end this valve rod is provided with a pair of spaced shoulders or abutments 35 and 36 which are circular or annular in shape and are adapted to slidably engage the interior surface of the packing gland or sleeve 30, and between these spaced shoulders or abutments I provide an elongated slot or recess 37 adapted to permit the passage of the trigger 9 therethrough. The packing gland or sleeve is provided on each side with elongated slots or openings 38 with which said elongated slot or recess 37 in the valve stem 33 is in alignment, and which likewise permit the passage of the trigger therethrough. The extreme rear end of the rod 33 is interiorly bored and screw-threaded as at 39, this bore leading entirely through the rear end portion and into the elongated slot or recess 37. This receives the screw-threaded end 40 of the adjusting rod 41 which extends rearward and is shown as being hexagonal in shape, passing through a corresponding bore 42 in a knurled adjusting nut or member 43. Of course, it is to be understood that while I show the adjusting rod 41 as hexagonal in cross section and the bore 42 of the member 43 as of similar cross section, these are merely preferred forms and a slideable connection between these two parts may be afforded in various other ways. In the claims I refer to this rod and bore as polygonal and that is intended to include any form having a plurality of straight sides as opposed to a circular and rotative engagement. The sleeve member 44 is exteriorly screw-threaded as at 45 to engage the interior threads 46 formed in the rear end portion of the chamber or compartment 28. This sleeve member 44 extends into engagement with the rear end of the packing gland and sleeve member 30 which is reduced as at 47 to fit a complementary reduced portion 48 formed interiorly in the forward end of the sleeve 44. The sleeve 44 having screw-threaded engage-

ment with the barrel and bearing against the rear end of the packing gland or sleeve 30, provides the means for varying the pressure on the packing material which is positioned 5 in front of the packing gland or sleeve 30 so as to prevent leakage of the fluid material through the various parts. The nut member 43 has a stud or projection 49 extending through the opening 50 in the end of sleeve 10 44 and is provided with the shoulder 51 engaging complementary shoulder 52 on the inside of the sleeve 44. The nut member 43 is freely rotatable in the end of sleeve 44. A spring member 53 is positioned about the adjusting rod 41 and the extreme rear end portion of the valve rod 33 engaging the end of the nut member 43 on the one hand and the rear shoulder or abutment 36 of the liquid valve rod on the other hand. This spring, 20 therefore, affords pressure for maintaining the valve on the end of the liquid valve rod 33 on its seat, as will be presently described. Furthermore, rotation of the nut member 43 and the adjusting plunger 41 will vary the 25 distance between the end of the nut member 43 and the rear shoulder or abutment 36 and thus vary the tension of the spring 53. The forward end 54 of the adjusting plunger 41 extends through the rear end portion of the 30 liquid valve rod into the elongated slot or recess 37, so as to be engaged directly by the trigger 9 when pulled or moved rearwardly. Therefore, the adjustment of the adjusting rod 41 will vary the distance the end 54 thereof projects into the elongated slot or recess 37 and determine the time when the trigger engages the said end and also vary the length of throw of the liquid controlling valve, it being understood that the relative time of 35 opening the air and the liquid control valve and the amount of opening of these valves are material and important factors in the operation of this device.

The forward end of the valve rod 33 is 40 provided with the tapered or bevelled valve head 55 and the forward portion of the valve rod is positioned within a liquid material receiving chamber or compartment 56 which is provided in the front sleeve member 57. This front sleeve member 57 has an elongated portion exteriorly screw-threaded as at 58 to fit corresponding screw-threads 59 formed on the inner surface of the bore or passage 29 formed in the front end portion of the barrel portion 2. The rear end of this sleeve 57 is solid except for a bore or passage 60 through which the liquid valve plunger 33 passes and in which it has a bearing. It is to be noted that this bearing is of considerable extent and with the bearing afforded by the end 31 of the packing gland or sleeve 30 securely holds the valve rod or plunger in proper alignment and affords an extended bearing surface of hard and long-wearing material.

The liquid material receiving chamber or 45 compartment 56 communicates with the material supply passage 61, which extends vertically through the downward extension 62. This downward extension 62 has its lower portions externally screw-threaded as at 63 to afford a connection for a hose or pipe leading from a suitable liquid container or to the material cup 64 shown in Figure 2. Surrounding the upper portion of this extension 62 is a vertical annular air passage 65 with which the horizontal and forwardly extending air passage 25 connects. This vertical annular air passage 65 in turn communicates with the horizontal annular air passage 66 formed in the front end of the barrel portion 2 and this passage 66 in turn communicates with the annular air passage 67 formed in the forward or head end 68 of the sleeve member 57. This passage 67 is shouldered as at 69. This head end is provided with a plurality of apertures or holes 70 leading from the front thereof into communication with the forward part of the air passage 67. This head end is also provided with the annular shouldered portion 71 which is exteriorly screw-threaded as at 72 to receive the nozzle holding collar or ring 73. The annular shoulder 71 provides a reduced forward end portion 74 which is smooth and slidably receives the nozzle member 75. The engaging part of the nozzle 75 is formed with a cylindrical inner surface 76 terminating with an engaging shoulder 77. The nozzle 75 also has an external annular rib or projection 78 over which an annular flange 79 on the nozzle holding collar or ring 73 engages. Due to the slideable engagement of the nozzle with the reduced end portion 74 of the sleeve 71 and the locking engagement of the flange 79 with the flange or projection 78, the nozzle is fixedly and securely held in fixed adjustment on the discharge end of the device as a whole.

The sleeve 71 is internally screw-threaded as at 80 at the entrance to the chamber or compartment 56 to receive the screw-threaded extension 81 formed on the rear end of the fluid tip 82. This fluid tip is provided with the straight shoulder 83 which tightly engages the forward face of the reduced head end 68 of the sleeve 57, having the hexagon shaped portion 84 adjacent thereto for engagement by a wrench or other tool. The fluid tip is provided with a curved conical extremital portion 85 leading up to the hexagon shaped portion 84 and on the end has the cylindrical discharge tip 86 which is reduced from the tapered conical portion and forms the annular shoulder 87. The fluid tip is bored entirely therethrough, the bore 88 through the forward portion being less in diameter than the bore 89 through the rear portion. The rear end of the fluid tip where the bore 89 opens forms a seat 90 for the valve 55 or the end of the valve rod 33. It

is seen, therefore, that the liquid material passes up through the passage 61 into the chamber 56 and when the valve 55 is moved off its seat 90, the liquid material will pass 5 through the bores 89 and 88 and emerge from the end of the fluid tip within the nozzle.

The nozzle 75 is shown and described in detail in my Patent No. 1,706,875, issued 10 March 26, 1929. This is what I term a fan slot nozzle which is of general cylindrical form and substantially hollow, the means of attachment to the end of the barrel portion of the device having previously been described. A conically shaped passage 91 extends through the major portion of the length 15 of the nozzle and leads to a cylindrical passage 92 in the front end thereof. This cylindrical passage leads to a flat fan shaped or arcuate slot 93. The cylindrical tube 86 of the fluid tip is positioned within the cylindrical passage 92 of the nozzle. The junction of the cylindrical passage 92 with the fan shaped slot 93, it being understood that the 20 diameter of the cylindrical passage is greater than the width of the slot, affords abrupt shoulders 94. These shoulders 94 assist in breaking up the liquid by diverting the direction of flow of the air and causing the air to 25 undergo a sharp change of direction and pass into and across the stream of liquid from the fluid tip.

A very important feature of this invention is the provision of means on the device itself 30 for regulating the pressure and flow of the air or other fluid through the device to the nozzle where it may be readily adjusted and regulated by the operator regardless of the place of use of the device and regardless of 35 the distance of the device from the fluid pressure container or the liquid container. It includes a valve or other shut-off medium 95 which has screw-threaded engagement in a screw-threaded bore 96 extending into the 40 side of the barrel portion of the device and across the port or passage 25, so that by screwing the device entirely down, the port or passage is closed entirely, and by unscrewing the device a greater or less degree, the pressure 45 and the rate of flow of the fluid to the nozzle is varied. The operator is, therefore, enabled to accomplish positive and direct adjustment 50 of the air pressure and rate of flow at all times as this valve or shut-off medium 95 is located 55 in the gun and right where the operator is doing the work. It is, of course, understood that this adjustment is in addition to the adjustment and regulation which may be accomplished by manipulation of the trigger, as of 60 course the amount of movement of the trigger regulates the amount and pressure of the air passing through the air passages.

The operation of the device is simple and 65 easily understood. When connected up to a suitable source of air pressure and when the

liquid material inlet is connected to a cup or larger container, pressure on the trigger and movement thereof to a sufficient distance results in forcing the air valve off its seat and the passage of air through the various ports or passages and out through the nozzle. Further movement of the trigger results in moving the liquid valve 55 off its seat and the passage of the liquid (the container being subjected to pressure) through the liquid ports or passages and through the bores 89 and 88 of the fluid tip into the nozzle where the liquid is atomized by the currents or streams of air engaging the same and passing out through the discharge orifice. When the painting operation is stopped and pressure released from the trigger, the spring constructions will return the trigger to its normal position and will first shut the liquid valve 55 on its seat to prevent the further supply of liquid and then will shut the air valve on its seat after sufficient air has passed through the device to completely clean the same and prevent dripping.

It is to be noted that the device is of unitary construction, as far as the body of the same is concerned and that all the working parts are mounted and positioned within the barrel portion and completely enclosed therein with the exception of the operating portion of the trigger, which, of course, projects so as to be manipulated by the operator. The valve plungers are positioned horizontally in the barrel and both are directly engaged by the trigger so that the opening pressure is applied directly to them. The parts may be readily assembled and disassembled. The valves and their seats are readily accessible for examination and repair and replacement. A fixed adjustment is provided for the nozzle and the adjustable air control valve on the device provides for proper adjustment of the air at all times. The device is comparatively easy and cheap to manufacture and assemble. The bearing surfaces for the movable parts are large and the bearings are composed of hard and long-wearing material. The air valve assembly and the liquid valve assembly are separate and are separately accessible and are each composed of a minimum number of parts requisite to obtain the desired result.

What I claim is:

1. In combination in a device of the character described, a body portion having a barrel portion with a nozzle construction at one end, liquid supply conduits leading to said nozzle, a liquid controlling valve assembly provided in said barrel portion including a valve having a plunger, bearing means for said plunger, a packing gland construction for said plunger and means extending from the rear end of the barrel portion for adjusting the position of the valve and plunger, said means including a polygonal shaped

shaft and an adjusting nut having a polygonal bore fitting said shaft.

2. In combination in a device of the character described, a body portion having a barrel portion with a nozzle construction at one end, liquid supply conduits leading to said nozzle, a liquid controlling valve assembly provided in said barrel portion including a valve having a plunger, bearing means for said plunger, a packing gland construction for said plunger and means extending from the rear end of the barrel portion for adjusting the position of the valve and plunger, said means including a polygonal shaped shaft and an adjusting nut having a polygonal bore fitting said shaft, with resilient means interposed between said nut and said valve plunger construction.

3. In combination in a device of the character described, a body portion having a barrel portion with a nozzle construction at one end, liquid supply conduits leading to said nozzle, a liquid controlling valve assembly provided in said barrel portion including a valve having a plunger, bearing means for said plunger, a packing gland construction for said plunger and means extending from the rear end of the barrel portion for adjusting the position of the valve and plunger, said means including a polygonal shaped shaft and an adjusting nut having a polygonal bore fitting said shaft, with resilient means interposed between said nut and said valve plunger construction, said shaft having a threaded engagement with said valve plunger construction.

4. In combination in a device of the character described, a body portion having a barrel portion with a nozzle construction at one end, liquid supply conduits leading to said nozzle, a liquid controlling valve assembly provided in said barrel portion including a valve having a plunger, bearing means for said plunger, a packing gland construction for said plunger and means extending from the rear end of the barrel portion for adjusting the position of the valve and plunger, said means including a polygonal shaped shaft and an adjusting nut having a polygonal bore fitting said shaft, with resilient means interposed between said nut and said valve plunger construction, said shaft having a threaded engagement with said valve plunger construction having a slot formed therein, a trigger mounted on said body and passing through said slot and the end of said shaft passing into said slotted portion to be engaged by said trigger when operated.

5. In combination in a device of the character described having a one-piece body portion formed with a handle and with a barrel portion, a nozzle construction at one end of said barrel portion, air and liquid conduits leading through said body portion to said

nozzle construction, an air control valve mounted in the air conduits and a liquid control valve assembly adapted to control the liquid conduit, and means for operating said valves, said liquid control valve including a valve having a plunger having an extended bearing within said barrel portion, a packing gland construction through which said plunger passes, resilient means for holding the valve closed on its seat and adjustable means adapted to be engaged by said operating means whereby the timing and the amount of movement of the liquid valve may be varied, said adjusting means including a flat-sided rod having a movable connection with the valve plunger and a flat-sided actuating member having a slideable engagement with said flat-sided rod.

6. In combination in a device of the character described having a one-piece body portion formed with a handle and with a barrel portion, a nozzle construction at one end of said barrel portion, air and liquid conduits leading through said body portion to said nozzle construction, an air control valve mounted in the air conduits and a liquid control valve assembly adapted to control the liquid conduit, and means for operating said valves, said liquid control valve including a valve having a plunger having an extended bearing within said barrel portion, a packing gland construction through which said plunger passes, resilient means for holding the valve closed on its seat and adjustable means adapted to be engaged by said operating means whereby the timing and the amount of movement of the liquid valve may be varied, said adjusting means including a flat-sided rod having a movable connection with the valve plunger and a flat-sided actuating member having a slideable engagement with said flat-sided rod, said resilient means bearing against part of said valve plunger and a part of said actuating member.

7. In a device of the character described in combination with the barrel portion having a bore therethrough leading to a nozzle construction, the nozzle construction having air and liquid ports and passages and having a valve seat in the liquid passage, a liquid controlling valve assembly including a sleeve member mounted in the forward end of said barrel portion and formed to provide a liquid receiving compartment and also provided with an extended bearing bore, a packing gland sleeve mounted in another portion of said bore and an adjustable sleeve fitting in the rear end of said bore and bearing against said packing gland sleeve, a valve having a plunger bearing in said extended bearing bore and bearing in said packing gland sleeve, and an adjusting member connected to said plunger and having means at the rear of said barrel portion for adjustment purposes.

8. In a device of the character described in

- combination with the barrel portion having a bore therethrough leading to a nozzle construction, the nozzle construction having air and liquid ports and passages and having a 5 valve seat in the liquid passage, a liquid controlling valve assembly including a sleeve member mounted in the forward end of said barrel portion and formed to provide a liquid receiving compartment and also provided 10 with an extended bearing bore, a packing gland sleeve mounted in another portion of said bore and an adjustable sleeve fitting in the rear end of said bore and bearing against said packing gland sleeve, a valve having a plunger bearing in said extended bearing bore and bearing in said packing gland sleeve, and an adjusting member connected to said plunger and having means at the rear of said barrel portion for adjustment purposes, said 15 plunger also having a pair of spaced annular shoulders adapted to have a slidable engagement with the inner surface of said packing sleeve.
9. In a device of the character described in 20 combination with the barrel portion having a bore therethrough leading to a nozzle construction, the nozzle construction having air and liquid ports and passages and having a valve seat in the liquid passage, a liquid controlling valve assembly including a sleeve member mounted in the forward end of said barrel portion and formed to provide a liquid receiving compartment and also provided with an extended bearing bore, a packing 25 gland sleeve mounted in another portion of said bore and an adjustable sleeve fitting in the rear end of said bore and bearing against said packing gland sleeve, a valve having a plunger bearing in said extended bearing bore and bearing in said packing gland sleeve, and an adjusting member connected to said plunger and having means at the rear of said barrel portion for adjustment purposes, said plunger also having a pair of spaced annular shoulders adapted to have a slidable engagement with the inner surface of said packing sleeve, and resilient means 30 interposed between one of said shoulders and said adjustment means.
10. In a device of the character described in combination with the barrel portion having a bore therethrough leading to a nozzle construction, the nozzle construction having air and liquid ports and passages and having a valve seat in the liquid passage, a liquid controlling valve assembly including a sleeve member mounted in the forward end of said barrel portion and formed to provide a liquid receiving compartment and also provided 35 with an extended bearing bore, a packing gland sleeve mounted in another portion of said bore and an adjustable sleeve fitting in the rear end of said bore and bearing against said packing gland sleeve, a valve having a plunger bearing in said extended bearing bore and bearing in said packing gland sleeve, and an adjusting member connected to said plunger and having means at the rear of said barrel portion for adjustment purposes, said plunger also having a pair of spaced annular shoulders adapted to have a slidable engagement with the inner surface of said packing sleeve, and resilient means interposed between one of said shoulders and said adjustment means.
11. In combination in a device of the character described having a body portion with a barrel portion provided with air and liquid supply conduits extending therethrough, said barrel portion having a bore to receive a liquid valve assembly which includes a valve having a plunger and bearing means for said plunger, a sleeve mounted within the forward end of said bore, said sleeve providing a bearing surface for said plunger and also providing a fluid receiving compartment, a fluid tip mounted in said sleeve and having a bore extending therethrough adapted to communicate with said fluid receiving compartment and the valve seated in the end of said bore, and a nozzle construction secured to the forward end of the barrel portion and having communication with the air conduits. 75
12. In combination in a device of the character described having a body portion with a barrel portion provided with air and liquid supply conduits extending therethrough, said barrel portion having a bore to receive the liquid valve assembly which includes a valve having a plunger and bearing means for said plunger and operating means for said plunger, a sleeve mounted within the forward end of said bore, said sleeve providing a bearing surface for said plunger and also providing a fluid receiving compartment, a fluid tip mounted in said sleeve and having a bore extending therethrough adapted to communicate with said fluid receiving compartment and the valve seated in the end of said bore, and a nozzle construction secured to the forward end of the barrel portion and having communication with the air conduits, said sleeve being provided with an external shoulder and with an external screw-threaded portion, said nozzle having a part fitting against said shoulder and also provided with an annular shoulder, a connecting collar having screw-threaded engagement with said screw-threaded portion of the sleeve and having means adapted to engage the annular shoulder on the nozzle to hold the same in fixed engagement relative to said sleeve and to said fluid tip. 90
13. A device of the character described including, in combination, a body portion having a barrel portion, said barrel portion being bored longitudinally, sleeve members threaded into the bored barrel portion at each end thereof, and a packing gland in said bored barrel portion intermediate said sleeve members and said packing gland being 95

held in position by one of said sleeve members.

14. In combination, in a device of the character described, a barrel portion having a bore extending therethrough and having a liquid passage and a valve seat in the liquid passage, a liquid controlling valve assembly including a sleeve member mounted in the forward end of said barrel portion and formed to provide a liquid receiving compartment and also provided with an extended bearing bore, a packing gland sleeve mounted in another portion of said bore and an adjustable sleeve fitting in the rear end of said bore and bearing against said packing gland sleeve, a valve for said seat and having a plunger bearing in said extended bearing bore and bearing in said packing gland sleeve, and an adjusting member connected to said plunger and having means at the rear of said barrel portion for adjustment purposes. 70
75

15. In a device of the character described, in combination with a barrel portion having a bore extending therethrough and having a liquid passage and a valve seat in the liquid passage, a liquid controlling valve assembly including a packing gland sleeve mounted in said bore and an adjustable sleeve fitting in the rear end of said bore and bearing against said packing gland sleeve, a valve for said seat and having a plunger bearing in said packing gland sleeve, and an adjusting member connected to said plunger and having means at the rear of said barrel portion for adjustment purposes, said plunger also having a pair of spaced annular shoulders adapted to have a slidable engagement with the inner surface of said packing sleeve. 80
